CERVICAL APPLICATOR

Joseph S. Heintz and Michael S. Cook,
Chicago, Ill.

Application March 1, 1937, Serial No. 128,506

4 Claims. (Cl. 128—261)

Our invention relates to the application of medicaments to the cervix, and includes among its objects and advantages the provision of an improved cervical applicator.

5 In the application of medicaments it is necessary that the cervix be supported in a stationary manner, and the air evacuated therefrom. Such withdrawal of the air from the cervix creates a negative pressure which co-operates with 10 the supporting action on the cervix to the end that the medicament may be effectively applied thereto.

An object of our invention is to provide an applicator in which the cervix is supported in an 15 effective manner and in which means is incorporated for withdrawing air from the cervix.

A further object is to provide an applicator in 20 which the medicament is delivered to the cervix in response to atmospheric pressure, and in which negative pressure in the cervix co-operates with the atmospheric pressure to deliver the medicament in an effective manner.

Another object is to provide an applicator in 25 which novel means is employed for locating the cervix within the co-operating part of the applicator and in which the atmospheric pressure is rendered operable for delivery purposes by merely opening a valve.

Another object is to provide an applicator having 30 a suction cup so constructed and arranged as to accurately locate and effectively support the cervix in the stationary manner through the aid of negative pressure and in which means is included for effectively breaking any suctional relation between the cup and the cervix, as when removing the applicator.

A further object is to provide an applicator devoid of complicated co-operating mechanical parts and in which novel means is employed for 40 loading the applicator with a medicament.

In the accompanying drawing:

Fig. 1 is an elevational view of an applicator embodying our invention;

Fig. 2 is a sectional view along the line 2—2 of Fig. 1;

Fig. 3 is a sectional view along the line 3—3 of Fig. 2;

Fig. 4 is a sectional view along the line 4—4 of Fig. 1; and

50 Fig. 5 is a fragmentary detail view showing the manner in which the applicator may be loaded with medicament.

In the embodiment selected to illustrate our invention we make use of a barrel 10 to one end 55 of which we connect a heavy suction bulb 12

having a bead 13 for increasing its suction action. A rubber suction cup 14 is attached to the opposite end of the barrel. Fig. 2 illustrates the barrel 10 as being provided with a corrugated reach 16 over which the neck 18 of the bulb 12 5 is stretched. The end of the neck 18 has abutting relation with the flange 20 carried by the barrel 10. A tube 22 is formed integrally with the suction cup 14 and is frictionally retained on the reduced reach 24 at the opposite end of 10 the barrel 10.

Within the barrel 10 we mount a tube 26 which has one end constricted at 28 to provide an opening 30 communicating with the cup 14. The tube 26 extends beyond the opposite end of the 15 barrel 10 and into an opening 32 in the bulb 12.

Upon the threaded part 34 of the tube 26 we mount a cup 36 which is normally closed by a cap or valve 38 arranged to abut the end of the cup 36 to prevent entrance of air. The cap 38 20 comprises a plate 39 and a sealing gasket 40. Two flanges 42 are formed on the plate 39, which flanges lie in overlapping relation with lips 44 attached to the cup 36. The overlapping flanges and lips are provided with aligned openings for 25 the reception of a pin 46 which carries a coil spring 48 having its ends abutting the cup 36 and the cap 38 for urging the same into closing relation with the cup.

Adjacent the tube 26 and within the barrel 10 30 we mount a small tube 50 which places the bulb 12 in communication with the cup 14. In constructing the device, the tubes 26 and 50 may be arranged in juxtaposed relation and imbedded in the barrel 10 by molding the latter about the 35 tubes from any suitable material.

The cup 14 terminates in a bead 52 and is provided with three small air vents 54 immediately below the bead. A small bead 56 is also formed within the bottom of the suction cup. 40 Figs. 1 and 2 illustrate the normal position of the cup 14 for cervix holding purposes while the dotted line illustration of the cup in Fig. 2 illustrates the folded back position of the cup for insertion purposes. After insertion, a slight reverse 45 pull on the applicator brings the cup back to its normal position. The bead 52 lends support to the cup 14 so as to prevent distortion thereof when it is being applied to the cervix. The bead also holds the cup in its folded back position, as 50 illustrated in dotted lines.

In operation, the tube 26 is filled with medicament and the cup 14 folded back to its dotted line position and anointed with medicament to facilitate insertion. The device is then inserted, 55

after which a slight rearward pull on the barrel returns the cup 14 to its normal position, at which time the bulb 12 is compressed to force the air therefrom. After the cup 14 has resumed its 5 normal position, it is applied over the cervix. With the cervix properly positioned within the cup, the bulb 12 is released, and as the bulb 12 returns to its normal position, the sucking action of the bulb evacuates the air from the cervix and 10 causes the cervix to be firmly supported within the cup. As the cup or valve 38 is opened, the suction effective on the medicament and atmospheric pressure cause the medicament to be quickly delivered through the constricted opening 15 38 into the cervix and thereabout. With the suction broken, the applicator is easily withdrawn.

Our applicator is automatic in operation. The suction feature not only provides effective support and retention of the cervix within the cup 20 but also co-operates with atmospheric pressure for automatically delivering the medicament thereto and about the cervix. Delivery of the medicament is consummated by merely opening the cap 38. Because of thorough evacuation of 25 air from the cervix, our applicator delivers the medicament into the cervix in an effective manner.

Our cup 14 embodies novel means for determining proper positioning of the cervix. The 30 openings 54 establish air bleeds which prevent the cup from gripping the vaginal wall or tissue beyond the cervix so that the suction action may be utilized for determining placement of the cervix within the cup. In other words, the suction 35 is not effective unless the cervix is positioned within the cup, at which time the openings 54 are sealed.

In placing the openings 54 underneath the bead 52 the bead will hold the tissue or the vaginal 40 wall out of sealing relation with the openings, thereby eliminating any counter-suction which might be effective when withdrawing the applicator. Ordinarily, the suction is effectively broken when the cap is opened, but the openings 54 provide effective means for preventing any back suction at the time of withdrawal. In effectively preventing any counter-suction when the applicator is withdrawn the medicament will remain where placed and will not be withdrawn with 50 the applicator. With the suction cup 14 folded back to its dotted line position, the bead 56 provides a gentle curvature as a leading edge which projects beyond the end of the barrel 10, thus affording protection against injury from the barrel.

Fig. 5 illustrates the manner in which the tube 55 26 may be loaded. We have provided the cup 36 with internal threads 58 for the reception of the threaded neck 60 carried by a collapsible tube 62 containing medicament. The cap 38 may be 60 moved back sufficiently far about its pivotal axis as to provide accommodation for the tube 62.

Without further elaboration, the foregoing will so fully explain our invention that others may, by applying current knowledge, readily adapt the 65 same for use under various conditions of service.

We claim:

1. A cervical applicator comprising a barrel having a cervix receiving suction cup attached to one end thereof, a compressible bulb attached to 70 the other end of the barrel, the latter having communication with the suction cup and the com-

pressible bulb, a medicament containing conduit extending through said barrel and the compressible bulb, said medicament containing conduit having communication with the suction cup and the atmosphere, and means for closing and opening the medicament containing conduit at a position outside the compressible bulb, the negative pressure relation between the suction cup and the cervix being such that atmospheric pressure delivers the medicament to the cervix when the 10 medicament containing conduit is opened to the atmosphere. 5

2. A cervical applicator comprising a barrel having a cervix receiving suction cup attached to one end thereof, a compressible bulb attached to 15 the other end of the barrel, the latter having communication with the suction cup and the compressible bulb, a medicament containing passageway extending through the barrel and having separate communication with the suction cup and 20 the atmosphere only, and means for closing and opening said last-named passageway at a position remote from the suction cup, said suction cup having an outwardly projecting bead, the ball of the cup being provided with an air bleed adjacent 25 said bead, said air bleed being sealed by the cervix when positioned inside the suction cup.

3. A cervical applicator comprising a barrel having a cervix receiving suction cup attached to one end thereof, a compressible bulb attached to 30 the other end of the barrel, the latter having communication with the suction cup and the compressible bulb, a medicament containing passageway extending through the barrel and having separate communication with the suction cup and 35 the atmosphere only, means for closing and opening said last-named passageway at a position remote from the suction cup, the negative pressure relation between the suction cup and the cervix being such that atmospheric pressure delivers the 40 medicament to the cervix when the said last-named passageway is opened to the atmosphere, said suction cup comprising resilient material and being foldable back upon itself, and an annular bead of gentle curvature inside the bottom of the 45 cup and projecting beyond the end of the barrel.

4. A cervical applicator comprising a rigid barrel having a cervix receiving suction cup attached to one end thereof, said suction cup comprising flexible material, air evacuating means attached 50 to the other end of the barrel, said barrel having communication with the air evacuating means and the suction cup through its bottom, a medicament containing conduit extending through the barrel and said air evacuating means, one end of 55 said medicament containing conduit having communication with the suction cup through its bottom, the other end of the medicament containing conduit having sealed relation with the air evacuating means and communicating with the atmosphere, and means for opening and closing the medicament containing conduit at a position exteriorly of the air evacuating means, the negative pressure relation between the cervix and the suction cup being such that atmospheric pressure 60 delivers the medicament to the cervix when the medicament containing conduit is opened to the atmosphere. 65
